UNITED STATES PATENT OFFICE.

CHARLES E. AVAN, OF LOS ANGELES, CALIFORNIA, ASSIGNOR TO JESSE C. MARTIN, JR.,
OF SAN FRANCISCO, CALIFORNIA.

METHOD OF LAYING BRICK.

Application filed May 13, 1922. Serial No. 560,791.

To all whom it may concern:

Be it known that I, CHARLES E. AVAN, a citizen of the United States, and a resident of Los Angeles, county of Los Angeles, State 5 of California, have invented new and useful Improvements in the Method of Laying Brick.

The hereinafter described invention relates particularly to the laying of firebox 10 brick, or blocks, in combustion chambers or furnaces, wherein the refractory brick are laid in a metallic housing or closure.

An illustrative embodiment of the invention is shown in the accompanying drawings, in which Fig. 1 is a vertical central 15 longitudinal section through a locomotive fire-box lined in accordance with the present invention.

Fig. 2 is a vertical transverse section on line 2, 2 of Fig. 1.

One embodiment of my invention is in setting fire brick in the metallic pan forming the bottom closure of a locomotive hydro-carbon fuel burning firebox in which heretofore it has been the practice in setting the fire brick therein to use a single kind of 25 joint mortar made of ground fire clay, or a combination of ground clay and ground brick to temper the clay against shrinkage.

The pan 3 in which the brick, or blocks, are set is commonly constructed of steel 30 plates with angle-iron reinforcement riveted thereto, although the pans may be made of welded steel plates, or by casting.

The pan is supported from the mud ring 4 of the locomotive firebox, and the ground or 35 prepared joint mortar is set between the pan and the brick, as well as between the brick for jointing between the same, being spread 40 with a trowel in the usual manner, the density or consistency of the mortar mix being the same, whether used between the pan and the brick as at 5, or between the brick 6 themselves. The general practice being the 45 use of riveted steel pans, a considerable amount of joint mortar is required, and at present used, to cover the rivet heads and 50 projecting plates at their juncture, and it is in forming a superior backing for the brick 55 next the steel pan, as well as a better jointing material between the brick at a less expense and in a more expeditious manner to meet the exacting requirements of locomotive oil fired furnaces with their vibratory 60 movement, that the advantages of my im-

proved method stand out even more prominently than in the stationary metallic cased refractory linings, where it is equally applicable, such as forge and heat treating furnaces, or the like.

The practice now prevailing particularly in locomotive oil burning furnaces of using a single consistency of ground joint mortar, or prepared material, normally sufficiently fluid to be applied with a trowel is objectionable in that through the jar and vibration of the locomotive the brick work is caused to loosen in its setting and the bricks to fall into the flame-way of the combustion chamber, which is not alone expensive in 65 cost of brick and its maintenance, but frequently causes engine failures in road service as steam cannot be maintained in the locomotive boiler as required, with brick precipitated in the path of the hydrocarbon 70 flame injected through the burner.

This failure in the brick work to remain set in place is brought about through the disintegration or pulverizing of the ground joint mortar material used between the pan 80 and the brick, the mortar sifting or settling down due to the vibration and finally forcing the brick setting open between the joints, breaking the walls and dropping the bricks into the pan and flame-way. This condition is further aggravated by the use of 85 thick mortar joints, as when fire brick are set in mortar laid between the brick with a trowel in the commonly prevailing manner when the same density of material is used 90 as at present for backing and jointing. The integrity and lasting qualities of the locomotive refractory lined firebox depends upon the ability of the backing and jointing material to withstand the service conditions 95 obtaining, which involve excessive jar and vibration; and it is one of the purposes of my invention to overcome the inefficiency of the present method of laying fire brick or blocks in locomotive metallic pans by eliminating a single consistency of backing and jointing material and providing in the place thereof a material of one consistency for 100 backing, and of another consistency for jointing, the backing material being of 105 greater density than the jointing material, so that the backing material will not disintegrate, powder or break up through the jar of service, and which backing material can, by thinning with water, be reduced in 110

- density to the consistency of thick cream, forming a wash for dipping the brick in so that no material or objectionable thickness of joint obtains between the brick when laid.
5. In practice the method of my invention makes it possible to produce a refractory structure, the laying of which places it without the province of the mason setting the brick to apply thick mortar joints between 10 the brick, and at the same time provides a backing material between the brick and the metal which, on account of its relatively stiff or non-fluid nature, beds itself into cracks or openings in the metallic housing 15 thereby tending to form a joint for the elimination of foreign air currents into the combustion chamber which detract from fuel economy.
- I have found that the plastic fire clays as 20 mined provide an excellent and inexpensive material for the purposes of my invention, the lump clay being readily slackened with water, or made plastic in conveniently made vats, being saturated clear through and prepared so that it is plastic, but stiff, to work. In this condition it may best be termed 25 "stiff" or "backing clay mud," and in practice it is spread or tamped into place to cover the rivets or projections of the pan, 30 requiring some little effort, on account of its stiff, plastic nature, to bed over the projections in making a good, level backing for the brick. The clay for use between the brick may be best termed "soft" or "dipping 35 mud," being a dilution or reduction in density of the stiff, plastic mud. In practice, I find it desirable in the use of some plastic clays, to dilute the stiff mud with salt water, or fluxing agent, in preparing the soft mud, 40 so that the dip will vitrify and form a bonding between the brick to best meet the temperature conditions of the fire box, it obviously being of material advantage to bond the joints between the bricks by reducing 45 the fusion point of the soft dipping mud, if the fusion point of the plastic clay used is known by test to be considerably higher than the furnace temperatures obtaining, as otherwise it would not serve the purpose as 50 efficiently.

The preferred material to be used in carrying out the methods of my invention is one in which a minimum of grit, such as free silica, or sand, exist, and in which one kind of material only need be used for forming both the stiff and soft mud, on account of its small cost and easy preparation, although two different materials, both of different

density—one for forming the stiff or backing mud, and the other for forming the soft or dipping mud—can be used in serving the purpose of my invention. For example: The plastic clay made stiff, can be used as a backing next the steel pan and a wash or soft mud jointing material of a character that would better withstand the temperature conditions of the furnace than the diluted stiff mud, could be used as a dip for jointing between the brick, without departing from the principle of my invention.

70

What I claim is:

1. The method of laying brick in a metallic casing, which brick when laid, are set in non fluid and fluid plastic clay consisting of placing the non fluid plastic clay between the casing and the brick whereby to form a backing for the brick and dipping the brick in the fluid plastic clay whereby to form a joint therebetween.

75

2. The method of laying brick in a metallic casing, which brick when laid, are set in material of two densities, consisting of placing the material of greater density between the casing and the brick to form a backing for the brick and dipping the brick in the material of lesser density to form a joint therebetween.

80

3. The method of laying brick in a metallic fire box casing, which brick when laid are set in clay material of two densities, consisting of placing the material of greater density between the casing and the brick to form a backing for the brick and covering the co-acting faces of the brick in the material of lesser density to form a joint there- 95 between.

90

4. The method of laying brick in a metallic fire box casing, which brick when laid are set in plastic clay material of two densities, consisting of placing the plastic clay material of greater density between the casing and the brick whereby to form a backing for the brick and covering the co-acting faces of the brick in the plastic clay material of lesser density to form a joint therebetween.

100

5. A structure adapted for use as a fire box comprising a metallic housing, a brick lining for said housing, a stiff plastic clay backing material between said brick and said housing and a fluid plastic clay jointing material between said brick.
